Primary Examiner—Louis S. Zarfas
Attorney, Agent, or Firm—Banner, Birch, McKie & Beckett**[57] CLAIM**

The ornamental design for a shoe sole periphery, as shown and described.

DESCRIPTION

FIG. 1 is a side elevational view of one side of a shoe sole periphery showing our new design;

FIG. 2 is a side elevational view of the other side of the shoe sole periphery shown in FIG. 1;

FIG. 3 is a front elevational view of a shoe sole periphery shown in FIG. 1;

FIG. 4 is a rear elevational view of the shoe sole periphery shown in FIG. 1;

FIG. 5 is a cross section taken along line 5—5 of FIG. 1;

FIG. 6 is a cross section taken along line 6—6 of FIG. 1;

FIG. 7 is a cross section taken along line 7—7 of FIG. 1;

FIG. 8 is a cross section taken along line 8—8 of FIG. 1;

FIG. 9 is a cross section taken along line 9—9 of FIG. 2; and,

FIG. 10 is a cross section taken along line 10—10 of FIG. 2.

The broken line showing of a shoe outsole and a shoe upper in FIGS. 1-4 are for illustrative purposes and form no part of the claimed design.
